UNITED STATES PATENT OFFICE.

HENRY LOUIS WYGERT, OF ALBANY, NEW YORK.

DENTAL VULCANIZER.

1,401,933.

Specification of Letters Patent. Patented Dec. 27, 1921.

Application filed June 14, 1921. Serial No. 477,454.

To all whom it may concern:

Be it known that I, HENRY L. WYGERT, a citizen of the United States of America, and resident of Albany, in the county of Albany and State of New York, have invented certain new and useful Improvements in Dental Vulcanizers, of which the following is a specification.

This invention relates to safety devices for vulcanizers and it has relation more particularly to controlling means for dental vulcanizers in which provision is made for conserving the heat or steam which has been generated during the vulcanizing process, pending the completion of repairs to the usual safety disk employed in connection with such vulcanizers, it being understood that the safety disks are provided to resist pressure below that which would prove dangerous, and the said disks being adapted to be fractured or blown upon the development of abnormal pressure within the vulcanizing machine.

It is an object of this invention to provide novel means actuated by the pressure released after the fracture of a disk for interrupting the supply of gases or other fuel which may be used in heating the vulcanizer; the said device also contemplating the provision of novel means whereby a safety disk may be applied to replace the fractured one without the loss of the steam charge which has been developed during the vulcanizing process. By reason of this invention, therefore, the vulcanizing process continues while the disk is being replaced, and the steam within the vulcanizer is not reduced in temperature to an appreciable extent during the short time required for replacing the safety disk under this method.

Heretofore, with many of the vulcanizers in common use, the fracture of the safety disk results in the discharge of the steam within the vulcanizer to a degree which interrupts the curing of the rubber, and as the process is carried on usually over a period of more than an hour, the time consumed prior to the blowing of the safety disk has been a complete loss, whereas by the present invention, the curing process is continued pending the repairing, as has been stated.

A still further object of this invention is to produce an attachment for vulcanizers in which an audible signal is operated in case the safety disk is blown, and simul-

taneously therewith, the flow of the fuel is interrupted.

With the foregoing and other objects in view, the invention consists in the details of construction, and in the arrangement and combination of parts to be hereinafter more fully set forth and claimed.

In describing the invention in detail, reference will be had to the accompanying drawings forming part of this application wherein like characters denote corresponding parts in the several views, and in which—

Figure 1 illustrates a sectional view of the head of a vulcanizer, showing the device embodying the invention applied thereto;

Fig. 2 illustrates a perspective view of a safety disk; and

Fig. 3 illustrates a disk retaining plug.

In these drawings 5 denotes a conventional head of a vulcanizer having a threaded nipple 6 to be secured to the body of the vulcanizer, the said nipple having a passage therethrough as at 7, terminating in branch ducts 8 and 9, one of which leads to a blow-off valve 10 which may be employed when the charge is to be exhausted from the vulcanizer and the other of which is in communication with a coupling 11 in the nature of a valve casing having a valve 12 therein, which may be turned to establish communication through the coupling when the port 13 of the plug registers with the passage 14 in the coupling, or to interrupt communication through the said passage when the valve 12 is in the position shown in Fig. 1. The coupling 11 has a nipple 15 threaded into the head and a seat 16 in its outer end for the safety disk 17, which has the characteristics heretofore indicated, the said disk being held on its seat by an apertured plug 18 which has a reduced portion 19 fitting in the seat of the disk and bearing thereon. A pipe 20 is connected to the outer end of the coupling 11 and it preferably has a bore 21 of the size 100 of the opening through the coupling, said pipe having an enlarged bore 22 at its outer portion where it is connected to or merges with a fuel supply pipe 23. The fuel supply pipe has a connection 24 with the source of fuel supply and a jet or nozzle 25 for delivering the fuel to be burned during the vulcanizing process.

There is, in the present embodiment of the invention, an inclined valve seat 26 in the 110

pipe 20 at the junction of the reduced and larger bore, and this valve seat has a valve 27 normally lying on it which interrupts communication between the small and large channels in the pipe 20. The valve 27 is oscillatably mounted as on a pivot 28, and it has an arm 29 which oscillates under the influence of the valve. When the parts are in normal positions, the valve 12 will be in position to establish communication through the passage 14 of the coupling, the pressure being sustained by the safety disk 17, under normal conditions of use.

Should the pressure within the vulcanizer become abnormal, the disk will be fractured and hence, the steam pressure will tend to lift the valve 27, and as the pipe 20 has a valve seat 30 therein to be engaged by the valve 27, the escape of steam will be prevented. The valve is only temporary for use in holding steam, since it is the purpose of the inventor that steam which has escaped through the safety disk shall operate a signal 31, so that an attendant may close the valve 12 and interrupt the escape of steam from the vulcanizer. The operation of the valve 27, however, serves to close a valve 32 in the fuel supply pipe 23, through the means of the arm 33 connected to the pintle 34 of the said valve 32, there being links 35 and 35' interposed between the arms 29 and 33, as fully shown in the drawings, the said links being oscillatable on a pivot 36. A spring 37 is connected to the arm 33 and to a stud 38, and the said spring normally exerts a pull on the arm 33.

The operation of the device has been indicated, in connection with a description of the elements, and one skilled in the art will, it is thought, understand the application in use of the said invention.

When an attendant closes the valve 12, he may disconnect the pipe 20 from the coupling and renew the safety disk, and as this can be accomplished expeditiously, there is no appreciable interruption of the firing of the vulcanizer. When the parts are to be restored to their normal conditions for operation, and the disk has been replaced and the parts restored to normal positions, the tension is taken off of the spring 37 and the valve 12 is opened slowly in order to obviate

sudden application of pressure to the disk, after which the fuel can be relighted and the process proceeded.

55

The disks 17 employed in these devices are usually of copper, having the characteristics above indicated.

I claim:

1. In a safety device for vulcanizers, a valve coupling connected to a discharge opening of the vulcanizer, a safety disk beyond the valve of the coupling, means for holding the disk in place, a pipe in communication beyond the disk, said pipe having a valve seat therein, the said valve being operated by pressure of steam escaping through the coupling, a fuel supply pipe, a valve therein, and means for communicating motion of the valve in the first mentioned pipe to the valve in the fuel pipe for closing the last mentioned valve, and means for holding the valve closed.

65

2. In a safety device for vulcanizers, a valve coupling connected to a discharge opening of the vulcanizer, a safety disk beyond the valve of the coupling, means for holding the disk in place, a pipe in communication beyond the disk, said pipe having a valve seat therein, the said valve being operated by pressure of steam escaping through the coupling, a fuel supply pipe, a valve therein, and means for communicating motion of the valve in the first mentioned pipe to the valve in the fuel pipe for closing the last mentioned valve, means for holding the valve closed, and a signal between the coupling and the valve in the first mentioned pipe.

70

3. In a safety device for vulcanizers, a coupling having a passage therethrough connected with the steam chamber of the vulcanizer, a valve for closing the passage through the coupling, a safety disk for guarding the passage through the said coupling, a pipe in communication with the coupling beyond the safety disk, a valve in the said pipe actuated by steam escaping through said pipe, a fuel supplying pipe for the vulcanizer, a valve therein, and means for communicating the motion of the valve in the pipe to the valve in the fuel supplying pipe.
